UNITED STATES PATENT OFFICE.

GEORGE H. BASS, OF WILTON, MAINE.

SHOE.

SPECIFICATION forming part of Letters Patent No. 252,715, dated January 24, 1882.

Application filed October 17, 1881. (No model.)

To all whom it may concern:

Be it known that I, GEORGE HENRY BASS, a citizen of the United States of America, residing at Wilton, in the county of Franklin and State of Maine, have invented certain new and useful Improvements in Shoes; and I do hereby declare the following to be a full, clear, and exact description of the invention, such as will enable others skilled in the art to 5 which it appertains to make and use the same, reference being had to the accompanying drawings, and to letters or figures of reference marked thereon, which form a part of this specification.

15 My invention relates to driving-shoes, and has for its object a means of securing the shoe firmly to the foot, obviating danger from slipping off of logs, as a result of the possible looseness of the shoe.

20 In the drawings, Figure 1 is a side elevation; and Fig. 2 a cross-section upon the line $x x$.

A is a shoe of ordinary construction. It has attached to the sole and secured around the instep the strap B, as shown. Near the toe of 25 the shoe is placed another strap, C. It is fastened upon each side of the sole, and its free ends are secured together by a suitable buckle, as shown. By the employment of the additional strap much greater security is afforded 30 to the person, the foot is held more firmly in the shoe, and all side motion of the toes and forward portion of the foot is prevented.

This shoe is intended to be used by lumbermen and others who have to tread upon floating logs, or in other dangerous employment 35 where it is necessary to secure the greatest firmness of footing.

I am aware that a single strap has been placed around the instep of a moccasin; but in this, while the instep is held firmly, the forward portion of the foot may move laterally and result in accident. In my invention the entire foot is made secure. There can be no lateral movement whatever of the foot or any part of it in the shoe, and consequently much 45 greater security is afforded than by any device patented for like purpose.

The straps are provided with buckles to permit them to be loosened when it is desired to remove the foot from the shoe.

50 What I claim is—

A boot or shoe having a strap, B, passing entirely over the instep portion of the upper, and a strap, C, over the toe portion, all substantially as shown and described.

55 In testimony whereof I affix my signature in presence of two witnesses.

GEORGE HENRY BASS.
